PROCESS FOR PRODUCING AN ANTIGEN FOR
USE IN THE DIAGNOSIS OF MALARIA AND
PRODUCT THEREOF

Anna Dean Dulaney, Memphis, Tenn., assignor
to The University of Tennessee Research Cor-
poration, Knoxville, Tenn., a corporation of
Tennessee

No Drawing. Application September 17, 1945,
Serial No. 616,959

5 Claims. (Cl. 167—78)

1

This invention relates to the production of an improved antigen for use in the diagnosis of malaria.

Complement fixation tests have been developed to aid in routine laboratory determination of malaria. They depend upon the use of antigens ordinarily produced as saline extracts in known manner from dried parasites ground with saline solution and successively frozen, thawed and centrifuged (Dulaney and Stratman-Thomas, J. 10 Immuno., 1940, vol. 39, pp. 247-255). While this procedure has proven dependable for such tests, yet the opinion is justified that the test is more specific than sensitive. Recognition of the diagnostic possibilities of the test emphasizes the need for a more sensitive antigen.

It is an object of the present invention to produce a highly active antigen for the diagnosis of malaria by complement fixation test by a simplified procedure avoiding the conventional successive freezing and thawing of the blood cells for the extraction of the antigen portion. Thus the time and cost of the process are both reduced materially.

It is a further object of the invention to improve the procedure by early separation of the parasite mass from the hemoglobin of the blood cells. This purification is highly advantageous in facilitating the extraction of the mass.

A further object of the invention is to diminish the color of the final product. This is highly important as it makes reading or interpreting the test much easier and certain.

An added feature of the invention is a great increase in the quantity of the antigen obtained from a given source due to the use of an extractant differing from the conventional saline solution. Specifically such an extractant may be a phosphate buffer solution or a barbiturate buffer solution.

Other objects of the invention and consequent advantages and improvements will be evident from the following detailed description of the preferred manner of carrying out my invention.

To obtain a parasite mass for use in obtaining my antigen I infected monkeys heavily with malaria through inoculation with the organism known as *Plasmodium knowlesi*. At the peak of development of the infection the monkeys were killed and the blood collected.

The erythrocytes were laked with distilled water, freeing the parasites for further treatment.

The parasites were washed with water and centrifuged to remove non-parasitic material as completely as possible. The parasites were then dried for subsequent use in the preparation of the antigen. This drying puts the material in form for accurate determination of quantities

2

for processing. It is otherwise difficult to measure the quantity of parasites being used or to proportion the extracting material.

The above preparatory routine is mainly preliminary to the principal feature of my invention and well known except in so far as the laking step which is a distinct departure from customary practice.

The parasites prepared as above and in either wet or dry form were ground with M/10 phosphate buffer solution of pH 7.8-8.0 prepared by the usual and well-known method such as is set out on pages 810 and 811 of Practical Physiological Chemistry by Hawk and Bergeim, tenth edition, 1931. While alternate freezing and thawing at room or refrigerator temperatures may be employed, it is found that the selection of the extracting solution obviates the need for this routine. The preferred practice as followed was to allow the preparation to stand at room temperature with frequent stirring for about one hour. Centrifugation yielded a deep brown opalescent supernate. The residue was repeatedly extracted with fresh buffer solution until recovery was negligible.

The relative antigenic activity was determined by titration with a strongly "positive" malaria serum. It was found that the buffer preparations were much more active than the usual saline extracts.

As a specific example of the improved process and to illustrate the comparative values of this and the conventional saline extraction, two 0.1 gram samples of the dried parasites were each ground with 10 cc. of phosphate buffer and labeled (a) and (b). A third or control sample was ground with 10 cc. of 0.9 percent sodium chloride and labeled (c).

The sample (a) was given the usual treatment by alternate freezing and thawing (four times) then centrifuged, yielding a clear brown supernate which was removed and designated P-FT-1. The residue was mixed with a further 10 cc. of phosphate buffer solution and the alternate freezing and thawing repeated. The supernate from centrifuging was almost colorless and was designated P-FT-2.

Two successive supernates P-FT-3 and P-FT-4 respectively were obtained in like manner. Both 50 were practically colorless.

The second sample (b) was allowed to stand at room temperature with frequent stirring for about one hour. On centrifugation a deep brown opalescent supernate (P-R-1) was obtained.

The residue was taken up in 10 cc. of buffer and stirred at intervals for a second extraction period of about an hour. The pale ambar opalescent supernate was designated P-R-2.

Two additional extractions were made yielding

faintly colored preparations P-R-3 and P-R-4 respectively. The final residue was taken up in 10 cc. of buffer solution, left in the refrigerator overnight and centrifuged to produce a supernate P-R-5.

For purposes of further comparison the sample (c) was frozen and thawed as was sample (a) but using 10 cc. amounts of 0.9 per cent sodium chloride solution and successive extracts obtained (S-FT-1; S-FT-2; S-FT-3 and S-FT-4 respectively).

By titration against a strongly "positive" malaria serum diluted 1:2½, the relative antigenic activity of each of the above extracts was determined. A known negative serum and anti-complementary controls were included. All tests with the negative serum and in the series containing no serum were negative. The highest dilution of each antigen giving a 4-plus reaction with the positive serum was recorded. The following table gives the antigen units per cubic centimeter observed for each extraction in each of the three procedures.

Extraction Number	P-R (buffer)	P-FT (buffer-frozen)	S-FT (saline)
1	640	320	80
2	160	160	20
3	80	160	20
4	80	80	20
5	20	-----	-----
Totals	980	720	140

It is apparent that the phosphate buffer preparations are much more active than the saline extracts and that the values are obtained in the earlier extractions.

A calculated total of 9600 antigenic units was obtained by four extractions with phosphate buffer solution at room temperature as against 7200 units by four freezings and thawings in phosphate and 1400 units by four freezings and thawings in saline solution.

A further example of the improved process was carried out by treating fresh or dried parasites with N/10 barbiturate buffer solution (pH 8.5) at room or refrigerator temperatures but otherwise in the same proportions and conditions as above described.

Either method yielded active antigens containing 320 to 640 units per cubic centimeter and additional quantities on repeated extraction.

A highly active antigen was prepared by extracting the wet parasites obtained from one monkey with barbiturate buffer solution as above outlined, first with 200 cc. and then with 50 cc. The combined extracts were cleaned of salts by dialysis against distilled water and subsequently concentrated in a semipermeable membrane at 5° C. to 40 cc. On centrifugation a supernate of 1280 units of antigen per cc. was obtained.

The antigen produced in the manner herein described is characterized by a marked increase in sensitivity as will be evident from the above tabulated results of tests. It therefore constitutes a novel product of materially enhanced utility.

Further details relating to the preparation of the antigen and its use in carrying out complement fixation tests for malaria are to be found in the article on the preparation and properties of antigens from *Plasmodium knowlesi* as published in the American Journal of Tropical Medicine, September, 1944, vol. 24, pp. 323-326, by the

inventor and D. B. Morrison. In this article (page 324) it is stated that "Highly active antigens may be prepared by treating wet or dried parasites with M/10 phosphate buffer of pH 7.8-8.0."

From the above description it will be evident that I have provided a material and distinct improvement in the process of preparing an antigen for complement fixation tests for malaria. The process is marked by simplification in routine with consequent saving in time and cost. The final product is improved in color and renders making the tests more easy and certain. Finally the quantity of antigen recovered has been substantially increased and the antigen found to have greater sensitivity or activity. Other incidental advantages are present and the invention is clearly subject to variation in minor details and factors within the scope of the appended claims.

The present application is limited to the phosphate buffer and process. The barbiturate buffer and process constitute the subject-matter of divisional application Serial No. 64,696, filed December 10, 1948.

25 What is claimed is:

1. The process of preparing an antigen for complement fixation tests for malaria from parasitized animal blood which consists in laking the blood cells, grinding the parasite mass in M/10 phosphate buffer solution of pH 7.8-8.0, allowing the mixture to stand for approximately one hour with frequent agitation and separating the antigen.

2. The process of preparing an antigen for complement fixation tests for malaria from the blood of animals infected with *Plasmodium knowlesi*, which consists in laking the blood cells, grinding the parasite mass in M/10 phosphate buffer solution of pH 7.8-8.0, allowing the mixture to stand for approximately one hour with frequent agitation and separating the antigen.

3. The process of preparing an antigen for complement fixation tests for malaria from the blood of animals infected with *Plasmodium knowlesi*, which consists in laking the blood cells, grinding the parasite mass in M/10 phosphate buffer solution of pH 7.8-8.0, allowing the mixture to stand for approximately one hour with frequent agitation, centrifuging to separate 50 supernatant antigen, repeating the extraction with fresh buffer solution and combining the several supernates.

4. The process of preparing an antigen for complement fixation tests for malaria from the blood of animals infected with *Plasmodium knowlesi*, which consists in grinding the parasite-containing mass in M/10 phosphate buffer solution of pH 7.8-8.0, allowing the mixture to stand for approximately one hour with frequent agitation and separating the antigen.

5. An antigen for complement fixation tests for malaria consisting of the extract in M/10 phosphate buffer solution of pH 7.8-8.0 of the parasites from the blood of an animal infected with *Plasmodium knowlesi*.
